HANDBAG

William C. Hiering, Millburn Township, Essex County, N. J., assignor to J. E. Mergoth Company, Newark, N. J., a corporation of Delaware

Application October 15, 1932, Serial No. 637,895

1 Claim. (Cl. 150—29)

This invention relates to improvements in hand bags, and more particularly to means for facilitating the attaching of bag covering material to hand bag frame members.

It has, heretofore, been the usual practice to attach bag covering material to frame members by sewing, but such a method obviously requires considerable time and greatly adds to the cost of manufacturing a bag. However, certain devices have been also presented to eliminate the necessity of sewing, such devices comprising generally the crimping or clamping of the bag covering material directly in a channelled frame member. While such devices represent an improvement over the sewing method of attaching bag covering material to frame members, they are objectionable in that it is somewhat difficult to satisfactorily and neatly crimp or clamp the covering material to all sections of a U-shaped frame member, and most frame members are of that shape.

It is an object of this invention to provide a device in which bag covering material is first attached to an inlay, and the latter is then easily clinched into position in a channelled frame member by suitably spaced tabs on the frame members, thus obviating the necessity of exerting considerable force directly on the frame member itself in order to insure the secure holding of the bag covering material.

A further object is to provide an inlay of special design to which the bag covering material is attached, and a frame member having a downwardly directed flange along the longitudinal section thereof to cooperate with the inlay to hold the inlay stably in position during the process of clinching the inlay to the frame member.

These and other advantageous objects, which will later appear, are accomplished by the simple and practical construction and arrangement of parts hereinafter described and exhibited in the accompanying drawing, forming part hereof, and in which:

Fig. 1 represents a perspective view of bag frame members and inlays embodying my invention,

Figs. 2 and 3 are perspective views showing steps of inserting an inlay in a frame member,

Fig. 4 is a perspective view of a modified form of the invention.

Fig. 5 is a perspective view showing the manner in which bag covering material is carried in the inlay.

Referring to the drawing, there is shown a pair 55 of hingedly connected bag frame members 3 and

4 of similar shape. Each frame member is of the U-shaped channel type with the channel opening outwardly and laterally relative to the frame and hand bag. The frame member comprises an inner side wall 5 having an upper flange 6 and a lower flange 7, said flanges being at right angles to the side wall 5. On the longitudinal section A of the frame member, the upper flange 6 is provided with a downwardly directed flange 8 parallel to the side wall. The lower flange 7 is provided with a plurality of spaced tabs 9 having perforations 10 to enable them to be easily bent upwardly for a purpose hereinafter explained.

The inlay is of U-shape to correspond to the shape of the frame member, and bag covering material 11 is clamped or crimped between the walls 12 and 13 of the inlay. The leg portions of the inlay which fit into the legs B of the frame member have walls of equal height while the longitudinal section of the inlay has one wall 14 of greater height than the outer wall 13.

In assembling the device, the wall 14 of the inlay is moved into position underneath the flange 8 as shown in Fig. 2, and the legs of the inlay are positioned in the legs B of the frame member. It will be readily seen that the inlay is now stably held in position by the flange 8, and the tabs 9 can now be conveniently and easily bent upward to permanently secure the inlay to the frame member, and the operation can be performed with greater speed than has heretofore been possible, thus lessening considerably the cost of labor in assembling hand bags.

In Fig. 4 is shown a modified form of the invention in which the upper flange 6 of the frame member is provided with a downturned flange 15 on the leg portions B as well as on the longitudinal section A. The inlay (see Fig. 5) is in sections, with each section having mitered ends to enable the formation of square corners, and having a wall 16 of greater width than the other wall 17. In assembling, the inlays are placed in the frame member and the tabs 9 are then bent upward to hold the inlay sections securely in the frame member.

An inlay with walls of equal width (see Fig. 5) can be used satisfactorily in the frame member shown in Fig. 4, in which case the lower edge of the downturned flange 15 is sufficiently spaced from the upper edge of wall 18 to accommodate the bag covering material at the same time tightly gripping the covering material. The flange 15 also serves as a means of ornamentation. Also, the longitudinal section and legs of an inlay having sides of equal width can be integral.

From the above description it will be seen that I have provided a simple and effective device for greatly facilitating the attaching of bag covering material to frame members.

5 While I have described the legs of the inlay as having walls of equal height, it is obvious that the legs may have one wall of greater height than the other, so that wall 12 might be substantially a continuation of wall 14, without departing from the spirit of my invention.

10 The foregoing disclosure is to be regarded as descriptive and illustrative only, and not as restrictive or limitative of the invention, of which obviously an embodiment may be constructed including many modifications without departing from the general scope herein indicated and denoted in the appended claim.

15 Having thus described my invention, what I claim as new and desire to secure by Letters Patent, is:

20 In a hand bag, a U-shaped metal frame mem-

ber formed from sheet metal of uniform thickness, said frame member having an inner side wall provided with upper and lower flanges, the upper flange of the longitudinal section of the frame member having a downturned flange, an inlay of channel shaped construction and U-shaped to correspond to the shape of the frame member, the leg portions of the inlay having walls of equal height, the longitudinal section of the inlay having an inner wall of greater height than the outer wall adapted to be positioned underneath the downturned flange of the longitudinal section of the frame, the leg portions of the inlay adapted to be positioned in the leg portions of the frame, and tabs integral with the lower flange of the longitudinal section, said tabs being bendable over the inlay parallel to the inner side wall of the frame member to securely clinch the inlay to the frame member.

WILLIAM C. HIERING. 20
